UNITED STATES PATENT OFFICE.

GEORGE M. LUDLOW, OF EVANSTON, ILLINOIS, ASSIGNOR TO SANITARY SCALE COMPANY, OF CHICAGO, ILLINOIS, A CORPORATION OF ILLINOIS.

DESIGN FOR A COUNTER-SCALE HOUSING.

Application filed March 6, 1926. Serial No. 16,816. Term of patent 14 years.

To all whom it may concern:

Be it known that I, GEORGE M. LUDLOW, a citizen of the United States, residing at Evanston, in the county of Cook, and State of Illinois, have invented a new, original, and ornamental Design for a Counter-Scale Housing, of which the following is a specification.

In the accompanying drawing, forming part of this specification,—

Figure 1 is a front elevation; Figure 2 an end elevational view; and Figure 3 a top plan view of a counter scale housing embodying my new design.

I claim:

The ornamental design for a counter scale housing as shown.

GEORGE M. LUDLOW.
